JOHN F. ASHLEY, OF DALLAS, TEXAS.

HOEING-MACHINE.

1,119,215.

Specification of Letters Patent.

Patented Dec. 1, 1914.

Application filed June 18, 1914. Serial No. 845,921.

To all whom it may concern:

Be it known that I, JOHN F. ASHLEY, a citizen of the United States of America, residing at Graham and Sante Fe streets, 5 Dallas, Texas, have invented certain new and useful Improvements in Hoeing-Machines, of which the following is a specification.

This invention as specified relates to new 10 and useful improvements in hoeing machines.

The object of the invention is to provide a machine of the character described which will embody a novel and efficient form of 15 double drive; said machine being driven from the two corresponding side transport wheels which makes possible a straight and even drive down the row eliminating side draft.

20 Another object is to provide a single hoe machine which will have a natural, smooth, easy and unvarying stroke as it passes through the row.

A further object resides in the provision 25 of means for varying or adjusting the length of the hoe arm.

Finally the object is to provide and develop a hoeing machine of the character described which will be strong and durable, 30 comparatively simple and inexpensive to manufacture and one whose working parts will not be likely to get out of working order.

With these and other objects in view the 35 invention has relation to a certain arrangement and combination of elements, an example of which is described in the specification, pointed out in the appended claims and illustrated in the accompanying drawings wherein;

Figure 1 is a plan view of the hoeing machine correlated with a portion of a carriage, cultivator, or other form of implement upon which the hoeing machine may 45 be mounted; only the portion of said cultivator being necessary to show the attachment of said hoeing machine being herein illustrated. Fig. 2 is a rear elevation of the hoeing machine correlated with a portion 50 of a cultivator. Fig. 3 is a sectional view taken upon the line *a—a* of Fig. 1 illustrating the form of one of the driving members of the hoeing mechanism. Fig. 4 is a side view of the adjustable hoeing arm, 55 some parts being shown in section. Fig. 5 is a view taken upon the line *b—b* of Fig. 4.

Referring now more in particular to the drawings, wherein the same reference characters designate identical elements throughout, the numerals 1 and 2 respectively designate a cultivator transport wheel and arched axle; the vertical portion of said axle being referred to by numeral 3. Substantial horizontal support brackets 4 with vertically upturned portion 5 are rigidly mounted by 60 *U* bolts 6 to the axle portion 3. A reach bar 7 is fixed, adjacent and parallel to the axle, to the support brackets and adapted to stiffen the structure and support elements hereinafter mentioned.

A drive shaft 8 is journaled in bearings 9 and 10 fixed to the support brackets 4. Said shaft carries fixed to each extremity pinions 11 and 12 which mesh with gears 13 and 14 fixed to the transport wheels by *U* 65 bolts 15. A drive gear 16 is fixed to the shaft 8, said gear being provided with a ratchet toothed hub 17. Said toothed hub is adapted to normally engage a slidable toothed cuff 18. A key way 19 is formed 70 in the cuff 18 and adapted to engage a key 20 fixed to the shaft. The cuff 18 and drive gear 16 are hollow bored as indicated by the numeral 21. A coil compression spring 22 is confined upon the shaft and within 75 the hollow portion 21 which subjects the engaged gear and cuff to a parting thrust. The pinion 11 has a toothed engagement 80 with a toothed cuff 23. A key 23^a fixed to the shaft provides a sliding disengagement 85 for the cuff 23. Said engaging members are hollow bored, a coil compression spring 24 subjects them to a tendency of disengagement. The bearing 10 is formed with flanges 25 and recessed portions 26. A pair 90 of vertical lever members 27 having eyes 28 are carried by the shaft 8 and disposed upon either side of the bearing 10 having their adjacent edges lying contiguous with the flanges 25 of the bearing 10. One of the 95 levers is provided with a horizontal arm 29 which passes through a slot 30 in the other lever member. A tube 31 is carried by the shaft and has its extremities lying contiguous with the cuff 18 and one of the lever members. The arm 29 is provided with a 100 handle 29^a.

It is seen how the compression of the two springs 22 and 24 will thrust the eyes 28 inward toward the recessed portions 26. 110 It is further seen that the pair of vertical levers is unified in relation and may be

pivoted forward about the shaft as a center. A forward displacement of the levers, through a slight pressure on the handle 29^a, will cause the vertical lever members to be 5 disengaged from the flanges 25 and cause the eyes 28 to drop within the recessed portion, which action disengages, through the pressure of the springs, the two slidable cuff members from the gear and pinion. 10 This action as seen disengages the driving relation over the shaft 8 of one of the transport wheels while the other wheel will continue to drive said shaft.

It should be understood that a hoeing 15 machine to be practical should be driven from both wheels, this being necessary to eliminate the side draft. This being the case it becomes necessary to provide one of the driving wheels with a device to cut off 20 its driving relation when turning corners, to prevent undue strain on the driving mechanism. A support frame, composed of a pair of horizontal brackets 33 fixed to the reach bar and extending forward and carrying 25 an angle member 34, is provided to carry the hoeing mechanism hereinafter described. A shaft 35 is journaled in bearings 36 and 37 carried by the members 34 and 7. A pinion 38 is fixed to one extremity of the 30 shaft 35 and engages the gear 16. The shaft extends forward through the angle member 34 and has fixed to its extremity a crank arm 39. A vertical support arm 40 is substantially fixed to the angle member 35 35 7 and is provided with bracket 41 which bracket and support arm carries a pin 42. A substantially vertical gyrating arm 43, provided with a slot 44, is carried by the pin 42. Said arm is provided with a slot 40 45 formed in its lower extremity. A bearing bracket 46 is fixed to the gyrating arm and connects with the crank arm 39, thereby, establishing a movable relation with the 45 50 gyrating arm. 45 A hoe arm 47 is correlated with the gyrating arm and provided with means of adjustment in length. Said hoe arm is provided with a cutting blade and slotted as indicated by 48. A rib 49 is fixed to the gyrating arm and lies within or engages the slot 48 of the hoe arm. Guide sleeves 50 are 55 fixed to the gyrating arm 43 and adapted to slidably retain the hoe arm in a close and stiff relation with the gyrating arm yet 60 allow it, as seen, to be subjected to a sliding adjustment within the sleeves and upon gyrating arm. To effect the adjustment of the hoe arm a substantially long vertical 65 adjusting lever 51 is provided, said lever has formed on its lower extremity an out-turned portion 52 which passes through the slot 45 and is fixed in an aperture in the hoe arm by a pin 53. The lever extends upward and is provided with a handle 54 65 which may be conveniently reached by the

operator of the machine. The lever is confined within a bracket 55 which is fixed to the gyrating arm. Said lever is toothed as indicated by the numeral 56 and adapted to engage a pin 57 carried in the walls of 70 the bracket. A spring pressed push rod 58 is provided and adapted to keep the lever teeth in engagement with the pin 57. It is seen how the lever may be used to adjust the length of the hoe arm, the sleeves 50 75 and the rib 49 keeping the correlated arm and gyrating arm in a strong and substantial relation. A coil tension spring 59 has one extremity fixed to the lower sleeve of the hoeing arm and the other fixed to the 80 bracket 41. A pair of arcuate guide members 60 and 61 are provided one upon either side of the associated hoe and gyrating arm, and fixed to the support frame. Said guide members guide and strengthen the structure 85 taking the thrust of the hoe arm as the machine passes down the row.

In the operation of the machine the crank arm is driven through its correlated driving elements a sufficient speed to cause the 90 cutting blade to pass through the row at the proper distance to leave the hilled cotton at the desired spaced distance; the spring 59 will absorb and modify the vibrations and thrusts of the fast moving gyrating and 95 hoeing arm; the arm imparting a gyratory motion to the associated hoeing arm, while the correlated slot 44 and pin 42 compensate for the reciprocating and gyrating action 100 of the hoe arm.

The invention is presented as including all such modifications as properly come within the scope of the following claims.

Claims.

1. In a hoeing machine of the character 105 described and in combination with a suitable carriage, a pair of support brackets, a reach bar fixed to the support brackets, a support frame carried by the reach bar, a support arm fixed to the support frame, a 110 drive shaft journaled on the support brackets, a drive gear fixed to the drive shaft, a second shaft, a pinion on said second shaft and meshing with the drive gear, a crank arm fixed to the said second shaft, a gyrat- 115 ing arm, a slot in the gyrating arm, a pin carried by the support arm and engaged in said slot of the gyrating arm, a bearing bracket fixed to the gyrating arm and correlated with the crank arm, a hoe arm, 120 guide members on the frame correlated with the hoe arm, sleeves fixed to the gyrating arm and carrying the hoe arm, an adjusting lever correlated with the hoe arm and a coil spring fixed to the hoe arm and support 125 bracket.

2. In a hoeing machine of the character described and in combination with a suitable carriage, a pair of support brackets, a reach bar fixed to the support brackets, a 130

support frame carried by the reach bar, a support arm fixed to the support frame, a drive shaft journaled on the support brackets, a drive gear fixed to the drive shaft, a 5 second shaft, a pinion on said second shaft and meshing with the drive gear, a crank arm fixed to the said second shaft, a gyrating arm, a slot in the gyrating arm, a rib fixed to the gyrating arm, a bearing bracket 10 fixed to the gyrating arm and correlated with the crank arm, a slot in the lower extremity of the gyrating arm, a hoe arm, a slot in the hoe arm and correlated with the 15 rib on the gyrating arm, an adjusting lever introduced through the slot in the lower extremity of the gyrating arm and fixed to the hoe arm, a coil spring correlated with the hoe arm, guide members on the 20 frame correlated with the hoe arm and means provided for throwing out of gear one of the drive or transport wheels and maintaining the other drive.

3. In a hoeing machine, of the character described and in combination with a suitable carriage, a pair of support brackets, a 25 drive shaft journaled on the support brackets, a shaft driven by the drive shaft, a crank arm fixed to the shaft, a gyrating arm

correlated with the crank, a rib integral with the gyrating arm, a hoe arm, said hoe 30 arm provided with a slot and adapted to correlate with the rib of the gyrating arm and a lever correlated with the hoe arm and adapted to adjust the length of said arm.

4. In a hoeing machine, of the character 35 described, and in combination with a suitable carriage, a pair of support brackets, a drive shaft journaled on the support brackets, a shaft driven by the drive shaft, a crank arm fixed to the shaft, a gyrating arm 40 correlated with the crank, a rib integral with the gyrating arm, a hoe arm, said hoe arm provided with a slot and adapted to correlate with the rib of the gyrating arm, guide sleeves encompassing the associated 45 gyrating arm and hoe arm, a tension spring correlated with the gyrating hoe arm and some fixed point and a lever adapted to adjust the length of the hoe arm.

In testimony whereof, I affix my signature in the presence of two witnesses.

JOHN F. ASHLEY.
